UNITED STATES PATENT OFFICE.

JOSEPH BECKER, OF NEW YORK, N. Y.

PIANOFORTE-ACTION.

Specification of Letters Patent No. 14,998, dated June 3, 1856.

To all whom it may concern:

Be it known that I, JOSEPH BECKER, of the city of New York, county of New York, State of New York, and a citizen of the 5 United States, have invented a new and Improved Mode of Constructing Pianoforte-Actions; and I do hereby declare that the following is a full and exact description thereof, reference being had to the accompanying drawings, and to the letters of reference marked thereon.

To enable others skilled in the art to make and use my invention, I will proceed to describe its construction and operation.

15 First, a bar of iron M^2 , Figure 1, and Fig. 4, Plate 2 rests on clamps of iron or metal M^3 , Fig. 4. On these are supported the key frame Q^4 , Fig. 6, Plate 3, and Fig. 4, Plate 2. This key frame is square, circular, octa- 20 gon, elliptical, or any other desired form. Across the top of the cylinder, or frame work of the main body of the piano, a plank or piece of metal L^2 , (Fig. 1, Plate 1,) in the center of which is a female screw L^3 25 (Fig. 4, Plate 2,) and supports an ornamental top M^4 (Fig. 4, Plate 2) which can be raised or lowered at pleasure.

The action frame N (Plate 2, Fig. 5) corresponds in shape to the piano, it is a 30 frame work consisting of a lever rim N' or damper rail, and an upper rim or hammer board y , connected to the lower rim N' by the rods or frame O , and rods $o' o' o' o'$; to the action frame is attached the action 35 rail board B^3 , (Plate 2, Fig. 5.) The action frame N' (Plate 2, Fig. 5) is cut in two pieces and connected by a spring N^3 . The whole of the action frame N is connected to the piano body A , by hooks, a'' Fig. 1, 40 Plate 1.

The hammer rail Y is covered with baize or cloth or other substance to prevent injury to the keys when they fall back as well as to prevent their giving any sound 45 from the wood—the action frame N completely encircles the piano body. N is also called the damper rail. On the top of the rods O is a small cap of brass or other metal upon which rests the damper rail N' 50 (Fig. 5 Plate 2) made to correspond with the shape of the piano and attached to it by spiral springs T , (Plate 3 Fig. 6). On

the damper rail N there is a block of wood S' for the purpose of receiving the head of the rod V which forces out the damper 55 N' by the action of a treadle W , (Plate 1, Fig. 1.)

Plate 3, is a plan of the piano, the key frame Q^4 and contains the keys or levers G^2 . The finger or lever keys F^2 are fastened 60 to the key frame by pivots F^3 passing over the keys or levers G^2 fastened to the side of the key frame by slits or jaws G^3 on the key frame. The keys G^2 cross the finger keys F^2 at any angle desired; through the 65 keys or levers G^2 at a proper point are regulating screws H^2 ; on the lower end is a leather cap resting on the finger levers F^2 ; on the end of these keys or levers is a jaw which plays on a pin J^2 . In the lower end 70 of the connecting rods Z , which are hollow, are fitted small wooden jaws J^3 , and into the jaw J^3 plays a lever K^2 , fastened through the jaws J^3 attached to the rim n' on the lower part of lever. 75

K^2 is a semi-circular wooden projection resting on the leather covering H^3 (Plate 1, Fig. 3.) On the upper end of the hollow metallic rod Z is also a similar jaw fitted in the end rod Z , with a jaw in it similar to 80 the jaws J^3 and connects the rod Z with the jack X . This jack rests against the hammer block X^2 . On the back of the hammer block X^2 , (Fig. 3, Plate 1,) there is a small hammer X^3 , called a hammer jack which 85 rests on a strap X^4 , attached to a rod or wire A^4 . X^5 is another hammer jack, and B^4 is the lever jack attached to the B^3 , the jack rail, (Fig. 3, Plate 1). Attached to X^2 is the hammer X^6 . 90

The wire A^5 is called the damper lifter, A^6 the damper lever attached to A^5 , and A^7 one of the dampers.

Operation: The finger levers G^2 raise the cross levers F^2 ; these raise or act on K^2 , 95 which raise the jack B^4 ; this operates on both the damper lifter A^5 and the jack X , which acts on the hammer block X^2 , and causes the hammer X^6 to strike the strings, and the damper A^7 to prevent the vibration 100 of sound, the lever wire A^4 to which the strap X^4 is connected draws back the hammer X^6 by the block X^2 ready to act when required.

What I claim and desire to secure by Letters Patent of the United States, is—

The double broken action as shown in Plate 1, Fig. 3, namely, as follows G², and G³, H², F², J², K², J³, J⁴, N', Z Z, B⁴, A⁴, X B³, Q, X⁴, X⁵, X³, X², the said part or parts being combined and acting together completing the whole arrangement of the

double broken arrangements as described in and set forth in the accompanying specifications.

JOSEPH BECKER.
